SHOE AND SHOE BOTTOM UNIT

Francis L. Brandt, Wakefield, Mass., assignor to
 United Shoe Machinery Corporation, Paterson,
 N. J., a corporation of New Jersey

Application May 25, 1932. Serial No. 613,406

10 Claims. (Cl. 36—76)

This invention relates to improvements in shoes and shoe bottom units. The invention is illustrated with special reference to its embodiment in shank pieces for turn shoes commonly known as "turn shanks" although it may advantageously be embodied also in reinforced insoles for McKay-sewed shoes or other shoes in which the insoles are initially cut substantially to their final marginal contour.

10 One object of the present invention is to provide an improved shoe bottom unit for use in conjunction with a heel-attaching fastener to brace the heel and stiffen the shank portion of a shoe.

To the accomplishment of this object, one feature of the invention consists in a shoe bottom unit prepared for the reception of a heel fastener and comprising a shoe bottom piece, for example, a "turn shank" filler piece, a reinforcing or stiffening member, such as a metallic shank stiffener, 20 located at the outer side of the shoe bottom piece and having a heel-fastener-receiving hole therein, and a heel-fastener-retaining member located at the inner side of the shoe bottom piece and having a heel-fastener-receiving hole therein, 25 said members and the shoe bottom piece being secured together, with said holes in alignment and unobstructed, by means of one of said members extending through the shoe bottom piece and having holding engagement with the other of 30 said members.

As herein illustrated, a heel-fastener is employed which consists of an ordinary wood screw and the heel-fastener-retaining member consists of a thin metallic plate having a hole which is 35 smaller than the head of the screw so that the screw cannot be pulled outwardly through the shoe bottom piece but will be permanently retained in position to fasten the heel securely to the shoe. The illustrated shoe bottom piece or 40 turn shank filler piece has a hole formed therein for receiving the screw and means is provided for securing together the component parts of the shoe bottom unit or turn shank piece consisting of prongs struck from the material of the screw-fastener-retaining plate. The illustrated prongs 45 project downwardly from the edge of the hole in the plate; extend through the hole in the filler piece and through the hole in the shank stiffener; are clenched over the edges of the hole in the shank stiffener; and are arranged around the 50 edge of the hole so as not to interfere with the passage of the attaching screw therethrough. Also, as illustrated, the retaining plate is made large enough to serve as a clenching plate for lasting tacks employed to secure the upper to the filler

piece, thereby insuring the production of a nailless heel seat in the shoe. Furthermore, the heel portion of the filler piece is preferably split to provide an integral flap for use in covering the clenching plate as well as the head of the heel-attaching screw.

Considered in another aspect, the invention resides also in a shoe having an improved shoe bottom unit incorporated therein, the shoe comprising a heel and a heel-attaching-fastener 65 which, as herein illustrated, extends through the component members of the shoe bottom unit and cooperates therewith in bracing the heel and stiffening the shank portion of the shoe.

The invention will be explained with reference 70 to the accompanying drawing in which,

Fig. 1 is a perspective view of a shoe bottom unit in the form of a shank piece for a turn shoe;

Fig. 2 is a bottom plan view of the turn shank piece shown in Fig. 1; 75

Fig. 3 is an edge view of the shank piece;

Fig. 4 is a sectional view, on an enlarged scale, taken along the line IV—IV of Fig. 2;

Fig. 5 is a sectional view of a portion of a turn shoe having the improved shank piece incorporated therein; and 80

Fig. 6 is a perspective view of the improved shoe bottom unit in the form of a reinforced insole for use in shoes other than turn shoes.

Referring first to Figs. 1 to 5, inclusive, which 85 show the invention embodied in a composite shank piece for a turn shoe, the improved shank piece comprises a filler piece 10 made of leather board or other suitable material, a reinforcing member consisting of a metallic shank stiffener 90 strip 12 which is located in a longitudinal groove 14 (Fig. 2) in the outer side of the filler piece, and a heel-fastener-retaining member consisting of a thin metallic plate 16 which is located at the inner side of the filler piece 10 beneath a thin 95 flap 18 which is formed integrally with the filler piece by splitting the rear portion of the latter. As shown, the filler piece 10 is shaped in marginal contour to correspond to the contour of the interior of the heel and shank portions of a shoe. 100 The shank stiffener 12 is made long enough to underlie the heel seat portion of the filler piece and the rear portion of the shank stiffener is provided with a circular aperture 20 (Fig. 2) for receiving a heel-attaching screw 22 shown in Fig. 5. 105 The fastener-retaining plate 16 is shown as being cupped to conform to the convexity of the heel portion of the foot and it is provided with a circular aperture 24 for receiving a heel-attaching screw, the aperture being adapted, as herein- 110

- after explained to prevent the head of the attaching screw from being pulled outwardly through the plate 16 and thus the plate 16 serves to retain the screw in heel-attaching position in the shoe.
- 5 As shown, the retaining plate 16 has a marginal contour corresponding to that of the heel portion of the filler piece 10, this construction adapting the retaining plate to serve also as a clinching plate for clinching the points of the lasting 80 tacks employed to secure the upper of the shoe to the filler piece. For the purpose of receiving the heel-attaching fastener the heel portion of the filler piece 10, beneath the flap 18, has preliminarily formed therein a circular aperture 26 85 (Fig. 4). For the purpose of attaching the shank stiffener 12 and the clinching plate 16 to the filler piece 10 so as to produce a unitary structure, the clinching plate 16 is provided with means adapted to extend through the hole 26 in the filler piece 20 and through the aperture 20 in the shank stiffener. As shown, this means comprises a plurality of prongs 28 which are struck up from the clinching plate 16 at the edge of the hole 26, these prongs being conveniently formed by means of 25 a punch die employed in making the hole 24.
- In assembling the above described parts the clinching plate 16 is applied beneath the flap 18 with the prongs 28 extending through the hole 26 in the filler piece and the shank stiffener 12 is 30 laid in the groove 14 of the filler piece, the hole 20 being placed over the outer ends of the prongs 28. The outer ends of the prongs 28 are then rolled over the edge of the hole 20 in the shank stiffener as shown in Figs. 2 and 4, so as rigidly to secure 35 both clinching plate 16 and the shank stiffener 12 to the filler piece with the holes in the clinching plate, the filler piece and the shank stiffener in coaxial alinement. The construction is such that lower portions of the prongs will snugly engage 40 the shank of the heel-attaching screw, while the portions of the prongs adjacent to the clinching plate are curved or bent sufficiently to provide a seat for the tapering lower face of the head of the attaching screw.
- 45 In Fig. 5 the composite shank piece above-described is shown incorporated in a turn shoe comprising also an upper 30, a tread sole 32, and a heel 34. The margin of the upper 30, as shown, is lasted over the turn shank filler piece 10 and is 50 secured to the latter by means of lasting tacks one of which is indicated at 36, the points of the lasting tacks being clinched over against the upper side of the filler piece by the action of the clinching plate 16 so that a nailless heel seat is 55 provided within the shoe. The heel attaching screw 22 extends through the hole 24 in the clinching plate 16, the hole 26 in the filler piece 10 and the hole 20 in the shank stiffener 12 and is screwed 60 into the heel. The prongs 28 snugly embrace the shank portion of the screw 22 but are shaped near 65 their base portions, as best shown in Fig. 4 to conform to the bevel of the head of the screw so that the upper surface of the screw head will be substantially flush with the upper surface of the clinching plate 16. As shown, the head of the screw 22 and the upper surface of the clinching plate 16 are covered by 70 means of the flap 18 of the filler piece so that no metal is exposed and visible in the interior of the shoe bottom. The shank stiffener 12 is countersunk within the groove 14 to such an extent that its outer surface is substantially flush with the outer surface of the filler piece thus enabling the tread sole to lie close to the filler piece. The 75 countersinking of the shank stiffener in the filler

piece also insures that the shank stiffener will not interfere with the pulling over and lasting of the upper margins. The above-described construction is such that the heel-attaching screw co-operates with the members of the composite shank piece in bracing the heel and stiffening the shank portion of the shoe.

The construction shown in Fig. 6 is similar to that shown in Figs. 1 to 4, inclusive, except that the shank stiffener 12 and the clinching plate 16 80 are shown assembled with a full length insole 100 instead of a filler piece such as the filler piece 10. A shoe bottom unit is thus provided for use in shoes other than turn shoes, for example, McKay-sewed shoes and shoes wherein an outer sole 90 is secured to the shoe partially or wholly by means of cement.

Having described my invention, what I claim as new and desire to secure by Letters Patent of the United States is:

1. A shoe bottom unit prepared for the reception of a heel-fastener, said unit comprising a shoe bottom piece, a reinforcing member located at the outer side of said bottom piece and having a heel-fastener-receiving hole therein, and a heel-fastener-retaining member located at the inner side of the shoe bottom piece and having a heel-fastener-receiving hole therein, said members and said bottom piece being secured together, with said holes in alinement and unobstructed, by means on one 100 of said members extending through said bottom piece and having holding engagement with the other of said members.

2. A shoe bottom unit comprising a shoe bottom piece having a heel-fastener-receiving hole 110 therein, a reinforcing member for the shoe bottom piece located at the outer side of the latter and having a heel-fastener-receiving hole therein, a heel-fastener-retaining member located at the inner side of the shoe bottom piece and having a heel-fastener-receiving hole therein, and means on one of said members extending through the holes in the shoe bottom piece and in the other of said members at the edges only of said 115 holes for securing all of said parts together with 120 said holes in alinement and unobstructed.

3. A composite shank piece for a turn shoe comprising a filler piece having a marginal contour substantially corresponding to that of the heel and shank portions of a shoe and having a 125 heel-fastener-receiving hole therein, a shank stiffener located at the outer side of said filler piece and having a heel-fastener-receiving hole therein, a heel-fastener-retaining plate located at the inner side of the filler piece and having a heel-fas- 130 tener-receiving hole therein, and a plurality of prongs struck up from the retaining plate and extending through the holes in the filler piece and shank stiffener for securing the retaining plate and the shank stiffener to the filler piece with 135 the holes in said parts in registration.

4. A shoe bottom unit comprising a shoe bottom piece having a heel portion corresponding in marginal contour substantially to that of the interior of the heel portion of a shoe, a reinforcing 140 member located at the outer side of said bottom piece and having a heel-fastener-receiving hole therein, a heel-fastener-retaining member located at the inner side of the shoe bottom piece and having a heel-fastener-receiving hole there- 145 in, said member being substantially co-extensive with the heel portion of said bottom member and adapted to serve as a clinching plate for lasting fasteners for securing a shoe upper to said bottom member, and means on one of said members ex- 150

tending through said bottom piece and having holding engagement with the other of said members for securing said members and said bottom piece together with said holes in alignment.

5. A shank piece for a turn shoe comprising a filler piece for the heel and shank portions of a shoe, said filler piece having its rear portion split to provide an integral flap at its inner side and having a heel-fastener-receiving aperture in its body portion beneath the flap, a shank stiffener located at the outer side of the filler piece and having a heel-fastener-receiving hole in its rear portion, a clenching plate located at the inner side of the filler piece beneath the flap and having a heel-fastener-receiving hole therein, and a plurality of prongs struck up from the clenching plate and extending through the holes in the filler piece and shank stiffener for securing the clenching plate and the shank stiffener to the filler piece with the holes in all of said parts in registration.

6. A shank piece for a turn shoe comprising a filler piece for the heel and shank portions of a shoe, the filler piece having a groove formed in its outer side and having a heel-fastener-receiving hole in its rear portion, a shank stiffener located in the groove in the filler piece and having a heel-fastener-receiving hole in its rear portion, a clenching plate located at the inner side of the filler piece and having a heel-fastener-receiving hole therein, a plurality of prongs struck up from the clenching plate and extending through the holes in the filler piece and shank stiffener for securing the clenching plate and the shank stiffener to the filler piece with the holes in all of said parts in registration, and a flap integral with the filler piece for covering the clenching plate.

7. A shoe bottom unit comprising an insole member, a shank stiffener plate located at the outer side of the insole member, a clenching plate located at the inner side of the insole member, prongs on one of said plates extending through the insole member and having holding engagement with the other of said plates for securing the plates and the insole member together, and a flap integral with the insole member for overlying said clenching plate.

8. A shoe bottom unit comprising an insole member having a heel-fastener-receiving aperture therein, a shank stiffener located at the outer side of the insole member and having a heel-fastener-receiving aperture therein, a

clenching plate for lasting fasteners located at the inner side of the insole member having a fastener-receiving aperture therein, and means integral with the clenching plate and extending through the apertures in the insole member and the shank stiffener for securing all of said parts together with said apertures in registration.

9. A shoe comprising a shoe bottom piece having a heel portion corresponding in marginal contour to that of the heel portion of the shoe, a shank stiffener located at the outer side of said bottom piece and having a hole in its rear portion, a clenching plate located at the inner side of said bottom piece and having a hole therein, means for securing the shank stiffener and the clenching plate to said bottom member, an upper, fastenings securing the upper to said bottom piece, said fastenings being clenched against said plate, a tread sole, a heel, and a fastener extending through said bottom member and through the holes in the clenching plate and the shank stiffener and into the heel for securing the heel to the shoe and for cooperating with the clenching plate and the shank stiffener to brace the heel and stiffen the shank of the shoe.

10. A turn shoe comprising a shoe bottom filler piece corresponding in marginal contour to that of the heel and shank portions of the interior of the shoe and having a hole in its heel portion, the rear portion of the filler piece being split to form an integral inner flap, a shank stiffener located at the outer side of said filler piece and having a hole in its rear portion, a clenching plate located at the inner side of said filler piece beneath said flap, said clenching plate having a plurality of prongs extending through the holes in the filler piece and in the shank stiffener and having holding engagement with the shank stiffener for securing the clenching plate and the shank stiffener to the filler piece and said clenching plate having a hole aligned with the holes in the filler piece and the shank stiffener, an upper, lasting tacks securing the upper to the said filler piece and having their points clenched against said clenching plate, a tread sole, a heel, and a screw-fastener extending through the holes in the clenching plate, the filler piece and the shank stiffener and into the heel for attaching the heel to the shoe, the head of the screw-fastener being covered by the flap on the filler piece.
